UNITED STATES PATENT OFFICE.

EDWARD B. HESS, OF BROOKLYN, AND JOSEPH M. STOUGHTON, OF YONKERS, NEW YORK, ASSIGNORS TO MECHANICAL IMPROVEMENTS COMPANY, OF NEW YORK, N. Y., A CORPORATION OF NEW YORK.

WRITING-MACHINE.

SPECIFICATION forming part of Letters Patent No. 691,626, dated January 21, 1902.

(Application filed July 19, 1901. Serial No. 68,975. No model.)

To all whom it may concern:

Be it known that we, EDWARD B. HESS, of the borough of Brooklyn, city of New York, and JOSEPH M. STOUGHTON, of Yonkers, county 5 of Westchester, State of New York, citizens of the United States, have invented certain new and useful Improvements in Writing-Machines, of which the following is a specification.

10 This invention relates to devices for feeding, guiding, controlling, and delivering paper sheets, cards, or envelopes ordinarily used in writing-machines to the platen and coacting parts. Its purpose is to control the paper accurately and efficiently at all stages of its 15 passage to and around the platen and to provide for the ready and accurate use of multiple sheets of paper or cards.

As will be hereinafter apparent, the invention 20 is applicable to various styles of machines, even to understroke machines, without substantial modification in the principles of construction and mode of operation. It has, however, been shown as applied to a 25 front-stroke or visible-writing machine.

We employ an endless-band paper-feeder so arranged that it will travel in contact with the surface of the cylindrical rotatable platen at a side of the platen where the printing 30 does not occur. It is preferably a unitary band or structure and is of such width as to contact or coöperate with both the central and end portions of the platen and is preferably of a width equal or substantially equal 35 to the greatest width of sheet the machine is adapted to receive. Cards or envelopes or wide sheets may, therefore, be fed without adjustment or change of any kind and will be efficiently held and fed or directed around the 40 platen. It may be feasible to divide such an endless carrier longitudinally into two or more parts and yet have them behave in the desired manner. It is believed, however, that the best results are obtainable when the carrier 45 is continuous transversely. Such a carrier should be of non-elastic material to obtain the best results, although the material may, perhaps, be more or less elastic and the carrier operate satisfactorily under proper 50 conditions. In order to insure a certain and

uniform feed, particularly where multiple sheets are fed to the machine, we provide that the endless carrier shall be driven positively, and it is best that when so driven it should have the same surface speed as the 55 platen. Such an endless carrier being so mounted and arranged with reference to the platen that when no paper is being fed the carrier bears upon the surface of the platen and the platen and carrier both being positively driven at the same surface speed during the feeding operation, it follows that the sheet or sheets inserted between them will be carried around the platen with accuracy and with a minimum disturbance of the relation 60 of the sheets where multiple sheets are fed. The carrier should be capable of yielding radially of the platen to permit the passage between the two members of multiple sheets of such thickness as may be desired, and it is 65 very much preferred that this capacity of the carrier should depend upon the parts upon which it runs and not upon its own elasticity.

An organization such as suggested comprising an endless-band carrier of non-elastic material and positively driven to run in the same direction as the surface of the platen at the same surface speed and in contact therewith involves a principle which, so far as is known, is entirely novel in this art. 75

While, as stated, the best results are obtainable by employing a unitary endless carrier of such width as to contact and coöperate at the same time with the central and end or lateral portions of the platen, some of the 80 advantages of this invention may be obtained by employing feed devices comprising two or more narrow endless bands arranged with reference to the platen as in the well-known Remington understroke machine or as shown 85 in the patent of Spiro, No. 463,464, making the bands, however, of non-elastic material and driving them positively at the same surface speed as that of the platen.

In connection with an endless carrier of the 90 character indicated guides or delivery members are employed which, in coaction with the platen, receive the cards or sheets from the endless carrier and while properly holding them during the act of printing deliver 95 100

them from the platen. These guides or delivery devices preferably consist of endless bands, which, as herein shown, are frictionally driven from the platen, and they are so mounted and disposed as to be capable of adjustment longitudinally of the platen, thus adapting them to hold adjacent the edges either relatively wide sheets of paper or relatively narrow cards or envelops. These guides so capable of adjustment may, however, be other than endless bands. For instance, they may be rollers or mere clamping-fingers, and in all cases they should be capable of such radial movement relatively to the platen as to permit them to receive, hold, and properly guide the greatest thickness of sheets or cards that may be delivered to them by the endless carrier. If they are endless bands, they may be elastic or non-elastic, and in the latter event their radial movement could be derived from the parts on which they are mounted.

So far as is known endless-band guides cooperating with that side or face of the platen where the printing occurs and adjustable longitudinally of the platen are new. Preferably in conjunction with them the endless-band feeder or carrier coacting with the off surface or side of the platen is employed, the conjoint use of these two organizations giving in a writing-machine ideal conditions and an inexpensive and simple construction.

In the machine herein illustrated and specifically described the feeding devices or endless carrier are located in rear (having reference to the line of travel of the paper) of the printing-line, and hence may coact with any portion of the platen. The subsidiary devices, which have been termed "guides," and which may also be endless bands, and which receive the sheet from the carrier or feed devices, may lie wholly beyond the printing-line or across—*i.e.*, on both sides of—the printing-line. These devices, coacting, as they should, with the printing-face of the platen, should be adjustable longitudinally of the platen to adapt them to sheets or cards of different width.

In the accompanying drawings, Figure 1 is a plan view, partly broken away, transversely through the central portion; Fig. 2, a front elevation; Fig. 3, an elevation of the right-hand end of the machine with the carriage-carrying rails in section; Fig. 4, a similar view of the left-hand end of the machine; Fig. 5, a detail view indicating the roller-bearing of the carriage upon the carrying-rails; Fig. 6, a detail transverse section showing only the platen, endless carrier, guides, and associated parts; Fig. 7, a like view showing the same parts in a different position; Fig. 8, a detail view showing one of the channel-arms in which the lower rolls of the endless guides are mounted; Fig. 9, a front elevation, and Fig. 10 a transverse section merely indicating an organization in which in lieu of end-

less-band guides ordinary clamping-fingers are employed.

The carriage is composed of end plates *a a*, tied together by bars. The carriage-rails *b b* are to be supported in any appropriate way in the frame of the machine. They are located, respectively, at the lower front and rear top parts of the carriage and are formed with longitudinal grooves, preferably *V*-shaped, in which run antifriction-balls *c*, spaced by a perforated plate *d*, Fig. 5, and embraced above by corresponding grooved rails or bars *e e*, forming part of the carriage. This structure affords a practical and very efficient mode of mounting the carriage. It has been deemed unnecessary to indicate a frame and carriage actuating devices. They, as well as the type-bar and other usual mechanism of a writing-machine, may, except as herein stated, be of any suitable character.

The platen *f*, of any usual character, has upon its shaft the usual hand-wheel. At one side of the platen—to the rear, as here illustrated—is mounted a pulley *g*, turning in bearings in the end plates *a a* and substantially equal in length to the platen. Around this elongated pulley or roller passes an endless band *h*, as wide, substantially, as the platen is long. Below the platen and somewhat in front of a vertical plane passing through its axis is a roller or pulley *i*, preferably of somewhat less diameter than *g*, but of equal length. The pulley *i* is supported in bearings in arms *k*, preferably curved somewhat to conform to the curve of the platen and pivoted in rear of the platen adjacent the ends of the roll *g* in brackets *m*, mounted on the end plates of the frame. The arms have projections extending upwardly and forwardly in the special construction shown from their pivots and have pivoted to their ends links *n*, which incline upwardly and somewhat rearwardly and are pivoted at their upper ends in the lower ends of downwardly and rearwardly extending radial arms *o*, attached to a rock-shaft *p*, mounted in bearings in the end plates.

In the normal position of the parts thus far described and as shown in Figs. 3 and 6 the endless-band carrier *h* bears upon the under face of the platen and being, as shown, substantially as wide as the platen is long makes contact with it centrally as well as at or adjacent its ends. Sheets of paper, cards, or envelops introduced between the platen and the endless carrier will take the direction indicated by the arrow in Fig. 6 and passing between these two members will be carried around under the platen. A spring *q*, to be applied, as shown in Figs. 6 and 7, to each arm *k* or otherwise, serves to draw the endless carrier against the face of the platen, but permits of its being forced away therefrom to accommodate different thicknesses of paper or cards introduced between them. Obviously if the rock-shaft *p* be turned in the

been indicated; but in lieu of the endless guide and delivery bands ordinary curved fingers 8, attached to an ordinary spring-bail 9, are shown, the fingers being adjustable 5 longitudinally on the bail by means of set-screws 10. This construction is shown merely for the purpose of illustrating that the endless carrier may be advantageously used with guide devices other than those shown in other 10 figures of the drawings.

Of course it is to be understood that the invention is not limited to the precise manner of mounting and operating either the endless-band carrier or the endless-band guides.

15 Figs. 1, 2, and 4 show line-space devices operated by a hand-lever 11. They are of ordinary construction and form no part of this invention.

20 The common device of crowning the rolls or pulleys upon which the bands run to cause them to travel accurately may be employed in this construction. The crowning, however, will be very slight, so as not to disturb, practically, the parallelism of the different 25 parts of the bands or their uniform coaction at all points with the surface of the platen. This crowning of the rolls would be so slight that it would not be perceptible in the drawings, and as it is a common expedient it has 30 been thought not desirable to exaggerate the drawings to illustrate it.

In the construction illustrated the printing line or point may be at 12, Fig. 3.

35 The term "cylindrical platen" used in the claims includes ordinary forms of rotary platens usable in writing-machines and which may be described generally as cylindrical, and does not require that the periphery of the platen shall be a perfect circle.

40 In this specification and in the claims the endless-band carrier has been described as positively driven. By this term is meant a definite driving of the endless carrier regardless of its frictional contact with the platen.

45 In the drawings the carrier is so shown as definitely or positively driven by reason of its bite or hold upon its positively-driven roll. As stated in this specification, however, the same result may be produced in other 50 ways.

We claim as our invention—

1. In a writing-machine, the combination with a rotatable cylindrical platen, of an endless unitary band carrier adapted to travel at 55 the same time in contact with the central and side portions of the cylindrical surface.

2. In a writing-machine, the combination with a rotatable cylindrical platen, of an endless unitary band carrier adapted to travel at 60 the same time in contact with the central and side portions of the cylindrical surface, and means for throwing the carrier out of operative engagement with the platen.

3. In a writing-machine, the combination 65 with a rotatable cylindrical platen, of an endless unitary band carrier adapted to travel at the same time in contact with the central and

side portions of the cylindrical surface, and means for throwing the carrier out of operative engagement with the platen and locking 70 it in such position.

4. In a writing-machine, the combination with a rotatable cylindrical platen, of an endless-band carrier running in contact therewith in the same direction and positively 75 driven at the same surface speed, whereby sheets fed between the platen and carrier are carried around the platen toward the printing-point by the conjoint action of the surfaces of the platen and carrier between which 80 the sheets travel.

5. In a writing-machine, the combination with a rotatable cylindrical platen, of an endless-band carrier running in contact with the central and side portions of the cylindrical 85 surface and positively driven at the same surface speed.

6. In a writing-machine, the combination with a cylindrical rotatable platen, of a unitary endless band carrier arranged centrally 90 of the platen and adapted to run in contact therewith, and means for driving the carrier at the same surface speed as that of the platen.

7. In a writing-machine, the combination 95 with a cylindrical rotatable platen, of a unitary endless band carrier of a width approximately equal to the length of the printing-surface of the platen and adapted to run in contact therewith, and means for driving the 100 carrier at the same surface speed as that of the platen.

8. In a writing-machine, the combination with a rotatable cylindrical platen, of an endless-band carrier running in contact therewith in the same direction and positively 105 driven at the same surface speed whereby sheets fed between the platen and carrier are carried around the platen toward the printing-point by the conjoint action of the surfaces of the platen and carrier between which 110 the sheets travel, and means for throwing the carrier out of operative relation with the platen.

9. In a writing-machine, the combination 115 with a rotatable cylindrical platen, of an endless-band carrier running in contact therewith and positively driven at the same surface speed, and means for throwing the carrier out of operative relation with the platen 120 and locking it in such position.

10. In a writing-machine, the combination with a rotatable cylindrical platen, of a positively-driven endless-band carrier traveling in contact with and in the same direction as 125 the surface of the platen, whereby sheets fed between the platen and carrier are carried around the platen toward the printing-point by the conjoint action of the surfaces of the platen and carrier between which the sheets 130 travel.

11. In a writing-machine, the combination with a rotatable cylindrical platen, of a positively-driven endless-band carrier traveling

direction of the hands of a watch, as viewed in Fig. 6, the effect will be for the radial arm *o* and link *n* to throw the arm *k* downwardly and move the endless carrier out of contact 5 with the face of the platen or to permit it to become so slack as to allow of the adjustment by the operator of a sheet or sheets already in the machine. The large surface of contact of the endless carrier with the introduced 10 sheets or cards carries them readily around under the platen as the platen is revolved and, incidentally—by friction, it may be—the contiguous surface of the carrier is caused to travel at the same speed as the paper. As 15 shown in Fig. 7, when the shaft *p* is rocked through a sufficient arc the toggle action of the arm *o* and link *n* will hold the carrier away from the platen. The rocking of this shaft may be conveniently accomplished by 20 means of a projecting hand-lever *q*, keyed thereto.

A further important feature of this invention is the positive driving of the endless-band carrier at the same surface speed that the 25 platen has. This may be conveniently done by means of a gear-wheel *r*, placed at one end of the platen and meshing with a pinion *s* on the shaft of the pulley *g*, Figs. 1 and 3. Experience has demonstrated that with an organization 30 of this kind cards or sheets of paper forming a pile or collection of very considerable thickness may be introduced and carried around the platen without disturbance of their relative arrangement with 35 quite the same facility that a single sheet or card may be handled. Aside from the advantages of operation, the structure is one of small cost, and the usual paper-table, along or over which sheets are fed to the machine, 40 may be dispensed with. While the endless band at all points of contact with the platen presses the intervening sheets against the platen, this is particularly so at the forward roll *i*, which is or may be distinctively a pressure-roll. 45

As shown in the main figures of the drawings, front guides or bands are arranged just above the roll *i* or forward portion of the endless carrier. These guides may be of appropriate width, but are relatively narrow, and 50 are so mounted and arranged as to be respectively independently adjustable longitudinally of the platen and capable of being moved away from the surface of the platen. 55 As shown in Fig. 6, these guides or bands *t* when in normal position press against and conform to the surface of the platen and are driven frictionally. When thrown outwardly for the adjustment of a sheet, they may pass 60 entirely out of contact with the platen, if desired, or bear lightly thereon, as shown in Fig. 7. Each band passes around a roller *u*, suitably adjacent the roller *i* and having bearings in the lower end of the curved arm *v*, 65 preferably of channel-iron to afford sufficient rigidity, turning at its upper end upon a bolt *w*, projecting laterally from a horizontal arm

x and having upon its end a pulley *y*, around which the band also passes. The horizontal arms *x* extend part way across the top of the 70 platen and each forms part of a block *z*, movable upon a square or angular bar *l*, extending between the end plates of the frame and upon which the blocks are capable of being adjusted longitudinally by means of set-screws, as shown. The rock-shaft *p*, before mentioned, passes through apertures in the arms *x* and in lugs *2*, also forming part of the blocks *z* and arranged, respectively, adjacent the arms *x*. From the shaft *p* between the 80 parts *x* and *2* project upwardly arms *3*, movable longitudinally on the shaft by means of slot-and-key connection and to which are pivotally connected the rear ends of links *4*, whose front ends are slotted to embrace a pin 85 *5*, fixed in the aperture *6*, Fig. 8, of the part *7* of channel-iron *v*, extending upwardly beyond its pivot-bolt *w*. When the rock-shaft is actuated by the hand-lever *q*, as already described, or otherwise the first action that is 90 commenced is the swinging of the endless carrier *h* away from the platen, following which the pin *5* comes against the end wall of the slot in the link *4* and the channel-iron arms *v* are swung upon their pivot-bolts *w* to 95 throw the band carriers *t* away from the platen. The band carriers are normally pressed against the face of the platen by the springs *50*, applied to the arms *k*. When the parts are thrown into position shown in Fig. 100 7, the band guides *t*, as well as the endless carrier *h*, are maintained in their outward position by the toggle action between the parts *n o*.

The rear roll of the endless carrier or that 105 at the entry side of the platen need not be movable toward and from the platen, while the front roll may be. The latter in the construction shown acts as a pressure-roll, and between the two the endless feeder or carrier 110 has a relatively long surface contact with the platen, and for that reason it is not necessary that there should be any great pressure between the platen and carrier. With ordinary feed-rollers contacting with the platen at single points only relatively greater pressure is 115 required to enable the machine to perform the ordinary operations expected of it. Such reduction of pressure, possible with the present organization, has a beneficial effect on 120 the action of the retaining-pawl acting on the platen ratchet-wheel, permitting more accurate seating of the pawl with less spring-pressure.

The guide-band rolls adjacent the roll of 125 the carrier and which, as shown, are pressure-rolls may be movable; but the other guide-rolls need not be, and the latter being placed a suitable distance from the face of the platen act, with the aid of the bands, to 130 deliver the printed sheets or cards from the platen.

In Figs. 9 and 10 an endless-band carrier of the construction already described has

in contact with the central and side portions of the cylindrical surface.

12. In a writing-machine, the combination with a rotatable cylindrical platen, of a unitary positively-driven endless-band carrier traveling in contact with the surface of the platen and of a width approximately equal to the length of the printing-surface thereof.

13. In a writing-machine, the combination with a rotatable cylindrical platen, of a positively-driven endless-band carrier traveling in contact with and in the same direction as the surface of the platen, whereby sheets fed between the platen and carrier are carried around the platen toward the printing-point by the conjoint action of the surfaces of the platen and carrier between which the sheets travel, and means for throwing the carrier out of operative relation to the platen.

14. In a writing-machine, the combination with a rotatable cylindrical platen, of a positively-driven endless-band carrier traveling in contact with the central and side portions of the cylindrical surface and means for throwing the carrier out of operative relation to the platen.

15. In a writing-machine, the combination with a rotatable cylindrical platen, of a unitary positively-driven endless-band carrier traveling in contact with the surface of the platen and of a width approximately equal to the length of the printing-surface thereof and means for throwing the carrier out of operative relation to the platen.

16. In a writing-machine, the combination with a rotatable cylindrical platen, of an endless-band carrier running in contact with the surface thereof, a roll for said carrier mounted a suitable distance from the platen at the entry or feed point and a second roll for the carrier adjacent the printing-point urged yieldingly toward the platen, and pressing the carrier against it.

17. In a writing-machine, the combination with a rotatable cylindrical platen, of an endless-band carrier running in contact with the surface thereof, a roll for said carrier mounted a suitable distance from the platen at the entry or feed point, a second roll for the carrier adjacent the printing-point urged yieldingly toward the platen and pressing the carrier against it and means for moving the second-named roll away from the platen.

18. In a writing-machine, the combination with a rotatable cylindrical platen, of an endless-band carrier running in contact with the surface thereof, a roll for said carrier mounted a suitable distance from the platen at the entry or feed point, a second roll for the carrier adjacent the printing-point pressed yieldingly toward or against the platen and means for moving the second-named roll away from the platen and locking it.

19. In a writing-machine, the combination of a rotatable cylindrical platen, a roll mounted adjacent thereto at the feed side, a gear rotating with the platen, and engaging a pin-

ion on said roll, a second roll, in front of the first one (i. e., toward the printing-point) and an endless-band carrier traveling around the rolls and in contact with the surface of the platen.

20. In a writing-machine, the combination of a rotatable cylindrical platen, a roll mounted adjacent thereto at the feed side, a gear rotating with the platen and engaging a pinion on said roll, a second roll, in front of the first one, an endless-band carrier traveling around the rolls and in contact with the surface of the platen, and means for moving the second-named roll away from the platen to move the endless carrier out of co-operative relation thereto.

21. In a writing-machine, the combination of a rotatable cylindrical platen, a roll mounted adjacent thereto at the feed side, a gear rotating with the platen and engaging a pinion on said roll, a second roll, in front of the first one, an endless-band carrier traveling around the rolls and in contact with the surface of the platen, and means for moving the second-named roll away from the platen and locking it in such removed position.

22. In a writing-machine, the combination with a rotatable cylindrical platen, of an endless-band carrier running in contact with the central and side portions of the cylindrical surface, and guides co-operating with the platen, adjustable longitudinally thereof, and adapted to receive the sheet from the endless carrier.

23. In a writing-machine, the combination with a rotatable cylindrical platen, of a positively-driven endless-band carrier running in contact with the surface of the platen, and guides co-operating with the platen, adjustable longitudinally thereof, and adapted to receive the sheet from the endless carrier.

24. In a writing-machine, the combination with a rotatable cylindrical platen, of a positively-driven endless-band carrier running in contact with the central and side portions of the cylindrical surface, and endless-band guides co-operating with the platen, adjustable longitudinally thereof, and adapted to receive the sheet from the endless carrier.

25. In a writing-machine, the combination with a rotatable platen of an endless-band carrier positively driven at the same surface speed as that of the platen and running in contact with the surface thereof, and endless-band guides co-operating with the platen, adjustable longitudinally thereof, and adapted to receive the sheet from the endless carrier.

26. In a writing-machine, the combination with a rotatable cylindrical platen, of an endless-band carrier co-operating with the surface thereof, endless-band guides co-operating with the platen, adjustable longitudinally thereof, and adapted to receive the sheet or sheets from the endless carrier, and means for moving the endless carrier and guides out of operative relation to the platen.

27. In a writing-machine, the combination

- with a rotatable cylindrical platen of an endless-band carrier positively driven at the same surface speed as that of the platen and co-operating with the surface thereof, endless-
5 band guides coöperating with the platen, adjustable longitudinally thereof, and adapted to receive the sheet or sheets from the endless carrier, and means for moving the endless carrier and guides out of operative relation to the platen.
28. In a writing-machine, the combination with a rotatable cylindrical platen, of an endless-band carrier coöperating with the surface thereof, endless-band guides coöperating with the platen, adjustable longitudinally thereof, and adapted to receive the sheet or sheets from the endless carrier, and means for simultaneously moving the endless carrier and guides out of operative relation to the platen.
29. In a writing-machine, the combination with a rotatable cylindrical platen of an endless-band carrier positively driven at the same surface speed as that of the platen and co-
15 operating with the surface thereof, endless-
25 band guides coöperating with the platen, adjustable longitudinally thereof, and adapted to receive the sheet or sheets from the endless carrier, and means for simultaneously moving the endless carrier and guides out of operative relation to the platen.
30. In a writing-machine, the combination with a rotatable cylindrical platen, of an endless-band carrier coöperating with the surface thereof, endless-band guides coöperating with the platen, adjustable longitudinally thereof, and adapted to receive the sheet or sheets from the endless carrier, and means for simultaneously moving the endless carrier and guides out of operative relation to the platen.
31. In a writing-machine, the combination with a rotatable cylindrical platen of an endless-band carrier positively driven at the same surface speed as that of the platen and co-
45 operating with the surface thereof, endless-
50 band guides coöperating with the platen, adjustable longitudinally thereof, and adapted to receive the sheet or sheets from the endless carrier, and means for simultaneously moving the endless carrier and guides out of operative relation to the platen and locking them in such position.
32. In a writing-machine, the combination of a rotatable cylindrical platen, a roll mounted adjacent the feed side thereof and at such distance therefrom as to afford the desired entrance, a second roll, in front of the first one, normally urged yieldingly against the platen, an endless-band carrier traveling about said roll, rolls arranged adjacent said second-named roll and normally urged yieldingly against the platen, corresponding rolls located at the delivery-point and mounted suitably adjacent the platen, endless guide and delivery bands traveling around the second-named sets of rolls in coöperative relation to the sur-

face of the platen, and means for adjusting the endless guide and delivery bands and their rolls longitudinally of the platen. 70

33. In a writing-machine, the combination of a rotatable cylindrical platen, a roll mounted adjacent the feed side thereof and at such distance therefrom as to afford the desired entrance, a second roll, in front of the first one, normally urged yieldingly against the platen, an endless - band carrier traveling about said roll, means for positively driving the endless-band carrier, rolls arranged adjacent said second-named roll and normally urged yieldingly against the platen, corresponding rolls located at the delivery-point and mounted suitably adjacent the platen, endless guide and delivery bands traveling around the second-named sets of rolls in coöperative relation to the surface of the platen and means for adjusting the endless guide and delivery bands and their rolls longitudinally of the platen. 75 80 85

34. In a writing-machine, the combination with a rotatable cylindrical platen, of an endless-band carrier adapted to run in contact with the surface of the platen, and endless-
90 band guides, also coöperating with the surface of the platen, and adjustable longitudinally thereof. 95

35. In a writing-machine, the combination with a rotatable cylindrical platen, of an endless-band carrier running in contact with the surface of the cylinder, endless-band guides adjustable longitudinally of the platen, and means for moving the carrier and guides out of operative relation to the platen. 100

36. In a writing-machine, the combination with a rotatable cylindrical platen, of a positively-driven endless-band carrier running in contact with the surface of the cylinder, endless-band guides adjustable longitudinally of the platen, and means for moving the carrier and guides out of operative relation to the platen. 105 110

37. In a writing-machine, the combination with a rotatable cylindrical platen, of an endless-band carrier running in contact with the central part of the platen-surface at the feed side thereof, and guides adjustable longitudinally of the platen and coacting with the side of the platen where the printing occurs. 115

38. In a writing-machine, the combination with a rotatable cylindrical platen, of a coöperating endless-band carrier running in contact with the feed side thereof, and guides located at the side of the platen where the printing occurs and adapted to receive a fed sheet from the endless carrier. 120 125

39. In a writing-machine, the combination with a rotatable cylindrical platen, of a positively-driven coöperating endless-band carrier running in contact with the feed side thereof, and endless-band guides located at the side of the platen where the printing occurs and adapted to receive a fed sheet from the endless carrier. 130

40. In a writing-machine, the combination

- with a rotatable cylindrical platen, of a positively-driven endless-band carrier running in contact with the platen at one side of the line of print and on the feed side of the platen,
5. and longitudinally-adjustable guides located on the side of the platen where the printing occurs and adapted to receive the sheet from the endless carrier.
41. In a writing-machine, the combination with a rotatable cylindrical platen, of an endless-band carrier positively driven coöperating therewith and located at one side of the line of print and on the feed side of the platen, and longitudinally-adjustable guides located
10. on the side of the platen where the printing occurs and adapted to receive the sheet from the endless carrier.
42. In a writing-machine, the combination with a rotatable cylindrical platen, of an endless-band carrier positively driven coöperating therewith and located at one side of the line of print and on the feed side of the platen,
15. and longitudinally-adjustable guides located on the side of the platen where the printing occurs and adapted to receive the sheet from the endless carrier.
- longitudinally-adjustable guides located on the side of the platen where the printing occurs and adapted to receive the sheet from the endless carrier, and means for throwing the carrier out of operative relation to the platen.
43. In a writing-machine, the combination with a rotatable cylindrical platen, of an endless-band carrier coöperating with the surface thereof, guides coöperating with the platen, adjustable longitudinally thereof, and adapted to receive the sheet from the endless carrier, and means for simultaneously moving the endless carrier and guides out of operative relation to the platen.
- In testimony whereof we have hereunto subscribed our names.
- EDWARD B. HESS.
JOSEPH M. STOUGHTON.
- Witnesses:
